UNITED STATES PATENT OFFICE

165,999

LADY'S STOCKING

Lewis Poole, Harriman, Tenn., assignor to Burlington Mills Corporation, Greensboro, N. C., a corporation of Delaware

Application August 10, 1951, Serial No. 16,227

Term of patent 14 years

(Cl. D47—7)

To all whom it may concern:

Be it known that I, Lewis Poole, a citizen of the United States and a resident of Harriman, county of Roane, State of Tennessee, have invented a new, original, and ornamental Design for a Lady's Stocking, of which the following is a specification, reference being had to the accompanying drawing forming part thereof.

In the drawing—

Figure 2 is a detailed plan view of the design of the reinforced heel and heel area proper of my invention.

I claim:

The ornamental design for a lady's stocking, as shown.

LEWIS POOLE.
